US00D900308S

(12) **United States Design Patent** (10) **Patent No.:** **US D900,308 S**
(45) **Date of Patent:** **** Oct. 27, 2020**

(54) **CATHETER ADAPTER**

- (71) Applicant: **Becton, Dickinson and Company**,
Franklin Lakes, NJ (US)
- (72) Inventors: **Jonathan Karl Burkholz**, Salt Lake
City, UT (US); **Ralph L. Sonderegger**,
Farmington, UT (US); **Bart D. Peterson**, Farmington, UT (US); **Bin Wang**, Sandy, UT (US); **Nathan Mitchell**, Murray, UT (US)

(**) Term: **15 Years**

(21) Appl. No.: **29/647,566**

(22) Filed: **May 14, 2018**

Related U.S. Application Data

- (62) Division of application No. 29/580,130, filed on Oct. 5, 2016, now Pat. No. Des. 819,802.
- (51) **LOC (12) Cl.** **24-02**
- (52) **U.S. Cl.** **USPC .. D24/112; D24/129**
- (58) **Field of Classification Search**
USPC D24/112, 114, 127, 128, 129, 130, 133, D24/141, 146, 147; D8/93, 97, 300, 310, D8/311
CPC .. A61M 5/158; A61M 5/1582; A61M 5/3243; A61M 2005/1583; A61M 2005/1586; A61M 2005/3227; A61M 25/0606; A61M 25/0612; A61M 25/0631; A61M 25/0637

See application file for complete search history.

(57) **CLAIM**

The ornamental design for a catheter adapter, as shown and described.

DESCRIPTION

FIG. 1 is a perspective front, top and side view of a catheter adapter.

FIG. 2 is a perspective front, top and side view thereof.

FIG. 3 is a front view thereof.

FIG. 4 is a rear view thereof.

FIG. 5 is a right side view thereof.

FIG. 6 is a left side view thereof.

FIG. 7 is a top view thereof; and,

FIG. 8 is a bottom view thereof.

The broken lines represent portions of the catheter adapter that form no part of the claimed design.

1 Claim, 6 Drawing Sheets
